MOLD

Paul M. Mueller, Rome, N. Y., assignor to Revere Copper and Brass Incorporated, Rome, N. Y., a corporation of Maryland

Original application June 5, 1941, Serial No. 396,696. Divided and this application June 12, 1942, Serial No. 446,723

14 Claims. (Cl. 22—153)

My invention relates to molds, particularly but not exclusively to those for casting elongated slabs of metal such as copper which are afterward reduced to sheets by rolling, the present application being a division of my co-pending application Serial Number 396,696, filed June 5, 1941.

The invention, which has among its objects the provision of an improved means for conducting the cooling medium in a split mold, will be best understood from the following description when read in the light of the accompanying drawings of several embodiments of the invention selected for illustrative purposes, the scope of the invention being more particularly pointed out in the appended claims.

In the drawings:

Fig. 1 is a side elevation of a mold according to the invention;

Fig. 2 is an end elevation of the mold according to Fig. 1 as viewed from the right;

Fig. 3 is an end elevation of the mold according to Fig. 1 as viewed from the left;

Fig. 4 is a section on the line 4—4 of Fig. 3, the line 4—4 also being placed on Fig. 5 for convenience in following the drawings;

Fig. 5 is a section on the line 5—5 of Fig. 1, with parts omitted;

Fig. 5^a is a fragmentary section on the line 5^a—5^a of Fig. 5, with parts omitted;

Fig. 5^b is a section on the line 5^b—5^b of Fig. 5, showing a detail;

Fig. 6 is a section on the line 6—6 of Fig. 2, with parts omitted;

Fig. 7 is a section on the line 7—7 of Fig. 6, with parts omitted, showing the upper portion of the mold;

Fig. 8 is a section on the line 7—7 of Fig. 6, with parts omitted and parts broken away, showing the lower portion of the mold;

Fig. 9 is a section on the line 9—9 of Fig. 2, with parts omitted; and

Figs. 10 and 11 are, respectively, sections on the lines 10—10 and 11—11 of Fig. 9.

The mold illustrated in the drawings is a vertical mold which, without limitation thereto, is particularly useful for casting slabs of copper and its alloys.

Referring to the drawings, the mold illustrated comprises a fixed mold part A and a complementary mold part B, the two being connected at one side for relative swinging about the axial line of the spaced vertically aligned pivot pins 1 (Figs. 1 and 2) and being adapted to be releas-

ably clamped together in a manner hereinafter explained.

As illustrated (see particularly Figs. 1, 2 and 5), the mold part A comprises a vertical, longitudinally extending, plate-like member 3, herein-after for convenience of terminology called a web. Integrally secured as, for example, by welding or casting, to each of the vertical edges of the web 3 is a vertical flange 5 projecting from opposite faces of the web so as to form a member which has approximately the shape of an I-beam in transverse cross-section. The web 3 and flanges 5 of the mold part A at their lower ends are shown integrally joined by welding or casting to a base 7 for supporting the mold and securing it to a suitable support.

The mold part B also comprises a vertical web 3, which in this case is integrally joined with edge flanges 9 to give the part B a cross-sectional shape approximating that of a channel-iron.

As illustrated, detachably secured to the inner face of the web 3 of each mold part A and B is a plate-like member 11 defining a face of the mold chamber. The members 11 are shown as secured to the webs 3 adjacent the edges of the latter by vertical rows of bolts 13, a horizontal row of bolts 15 at the top of the mold, and a horizontal row of bolts 17 at the bottom of the mold.

Opposite the plates 11 each of the webs 3 adjacent its upper and lower end is provided with a transverse stiffening rib 21 (Figs. 1, 4 and 5), these ribs being integrally formed, by welding or otherwise, with the web 3 and edge flanges 5 or 9. As shown, the ribs 21 are in the form of channel-irons, the flanges of which are integral with the web 3. At about the mid point of the length of each mold part A and B is a transverse partition rib 23 in the form of a plate integral with the web 3 and edge flanges 5 or 9, and extending

between this rib 23 and the ribs 21 are vertical ribs 25 also in the form of channel-irons integrally joined to the web 3 and likewise to the rib 23 and ribs 21. The interior spaces of the channels formed by the ribs 21 and 25 are in communication, as clearly shown by Fig. 4, the rib 23 serving as a partition to divide the channel formed by the upper rib 25 from the lower rib 25. At opposite sides of the partition rib 23 and extending between the ribs 25 and the edge flanges 5 or 9 are transverse ribs 27 also in the form of channel-irons and integrally joined with the ribs 25, the webs 3, and edge flanges 5 or 9. Each of the ribs 27 at the right of the ribs 25, as viewed in Figs. 1 and 4, communicates with

55 the adjacent rib 25. In a manner hereinafter

explained, the lower ribs 27 at the right of the ribs 25, as viewed in Figs. 1 and 4, of each mold part communicate with a common inlet connection 29, carried by the mold part A, for water or other cooling medium, while the upper ribs 27 at the right of the ribs 25 communicate with a common outlet connection 31 carried by the mold part A.

Interiorly of the cooling medium passages afforded by the channel-shaped ribs 21, each web 3 is provided with perforations 33 (Fig. 4) which communicate with vertical longitudinal grooves 35 formed on the face of the web 3 adjacent the plate 11. These grooves are closed by the plates 11 and provide channels for the cooling medium. The water or other cooling medium from the inlet connection 29, as clearly indicated by the arrows in Fig. 4, enters the passages formed by the adjacent right hand rib 27 and flows downwardly through the communicating channel formed by the lower rib 25 and enters the channel formed by the lower rib 21. From this latter channel it is distributed by the adjacent perforations 33 to the channels 35, and flowing upwardly through these channels discharges through the upper perforations 33 into the channel formed by the upper rib 21, whence it flows downwardly through the upper rib 25 and from there through the communicating channel formed by the upper rib 27 at the right of this rib 25 to the outlet or discharge connection 31. In this way the plates 11, which preferably are formed of good conducting material such as copper, are effectively cooled. The approximate I-beam and channel-iron constructions of the body portions of the mold parts A and B in conjunction with their stiffening ribs form very rigid supports for the plates 11, which latter are permitted to expand and contract by reason of the clearance in the bolt holes for the bolts securing the plates to the webs 3, yet without warping on account of the rigidity of the stiffened webs 3 against which the plates are tightly held by the clamping means hereinafter described.

In the construction illustrated bars 37 defining the sides of the mold chamber are detachably secured to the edge flanges 5. As shown, these bars are provided with studs 39 (Figs. 1 and 5) projecting through perforations 41 in the adjacent edge flanges 5, and are rigidly clamped to the bars by nuts 43 carried by the studs. As illustrated in Fig. 5, a series of washers 45 of different thickness are placed between the nuts 43 and the adjacent side of each flange 5. One or more of these washers, or all of them, may be placed at the opposite side of the flange so as to lie between the flange and the adjacent bar 37, and by so positioning them the width of the mold chamber may be varied say, for example, by moving either or both bars 37 to their dotted line positions shown in Fig. 5. So that the washers 45 may be readily removed and replaced without the necessity of detaching the side bars from the edge flanges 5, the washers are preferably formed with radial slots 46 of width the diameters of the studs 39, which slots open into the stud receiving bores of the washers to give the latter a U-shape as shown in Fig. 5b. This construction provides a rigid support for the side bars 37, the bars being permitted to expand and contract longitudinally by reason of the clearance between the stud bolts 39 and the walls of the perforations 41, yet the bars are strongly held against the flanges 5 by the nuts 43 and are strongly clamped between the plates 11 to prevent warping of the bars.

As shown, the side bars 37 are provided adjacent their surfaces defining the sides of the mold chamber with longitudinal bores 47 for the cooling medium, which construction acts to keep the bars cool and to prevent transfer of heat to the flanges 5 so that the latter will not tend to warp. As shown in Figs. 7 and 8, the upper and lower ends of the bores 47 are closed by plugs 49, and are provided with lateral bores 51 communicating with short lengths of pipe 53. These pipes slidably extend through perforations 55 in the flanges 5 so that the side bars may be adjusted by use of the washers 45 on the studs 39 in the manner hereinbefore explained, the upper perforations at least having considerable clearance with the pipes to permit the bars freely to expand and contract longitudinally. To the outer ends of the pipes 53 are secured short lengths of flexible hose 57 leading to pipe nipples 59 carried by the edge flanges 5. These nipples place the hose in communication with the channels formed by the adjacent upper and lower channel-shaped ribs 21, as shown in Fig. 6, so that the cooling medium from the inlet connection 29 may enter the lower ends of the bores 47 and flow upwardly and discharge from the upper ends of the bores and be carried off by the outlet connection 31 for the cooling medium.

As illustrated, the bottom of the mold chamber 30 is defined by the upper surface of a bar 61 (Fig. 8) carried by the mold part A. This bar, which preferably is of cast iron, is secured against the adjacent side of the plate 11 of the mold part A by the bolts 17 which secure that plate to the adjacent web 3. The bar 61 is of such length as to extend under the opposite side bars 37, and is adapted to be strongly forced against the lower ends of the latter by screw jacks 63, which jacks are adjustably screwed into the base 7 of the mold part A and have lock nuts 64 to prevent them from accidentally backing off. The clearance about the bolt holes for the bolts 17 permits sufficient movement of the bar 61 to permit it to be so forced by the jacks 63, and permits longitudinal expansion and contraction of the bar, yet the jacks 63 prevent warping of the bar, and, by forcing them against the lower ends of the side bars 37, insures against entrance of metal between the upper face of the bar 61 and the ends of the side bars.

The means for pivotally supporting the mold parts A and B is best shown by Figs. 1 to 5. As illustrated, to one of the flanges 5 of the mold part A are rigidly secured spaced brackets 67 which carry the vertically positioned pivot pins 1 hereinbefore referred to. These pins serve pivotally to secure links 69 to the ends of the brackets, which links, as shown, are of rectangular cross-section (Fig. 4). Preferably the construction is such that no lateral lost motion exists in the hinged joints so formed, the pins making tight joints with the perforations in the brackets and links which receive them. Rigidly secured to the flange 9 of the mold part B adjacent the links 69 are blocks 71 having perforations 73 through which the links slidably extend and in which they fit. At the outer ends of the links are pins 74 which pivotally secure thereto yoke bars 75 extending across the mold part B to the opposite side of the mold. To the edge flange 5 of the mold part A at that side are secured spaced brackets 77 to the outer ends of which at 79 are pivotally secured the ends of links 81, the latter removably extending through the openings 75 formed by the bifurcated adjacent ends 83 of the

yoke bars 75 and adjustably carrying nuts 85 resting against the outer surfaces of the yoke bars at those ends so that the yoke bars may be forcibly drawn toward the mold part A to clamp the mold part B between it and the yoke bars.

As shown, the mold part B is provided with a plate 87 beneath each yoke bar, the plate being notched to permit the ribs 25 to pass through it and fitting the exterior of those ribs at the outer surface of the web 3 and adjacent parts of the edge flanges 9 and being welded thereto or being otherwise integrally formed with the body of the mold part B. As illustrated (see Fig. 5a), the intermediate portion of each yoke bar is channel-shaped in cross-section, the adjacent plate 87 fitting within this channel and being pivoted to the yoke bar by a pin 89, the aligned holes 91 in the yoke bars for receiving the pins being elongated in the direction of the lengths of the yoke bars, as shown in Fig. 5, so that the mold part B may move longitudinally of those bars.

The combined structure for pivotally securing the mold part B to the mold part A and for clamping the two together permits the mold part B to adjust itself toward the mold part A and transversely thereof, while forcing the mold part B to swing around the aligned axes of the pivot pins 1. This permits slight variations in the thickness of the side bars 37 and bottom bar 61 so that the thickness of the casting may be varied, and permits the surfaces of the plates 11 defining the faces of the mold chamber to be finished from time to time and takes care of discrepancies in manufacture of the parts.

As illustrated (see Figs. 1, 3 and 4), the outer side of the edge flange 5 of the mold part A opposite the flange 5 thereof which carries the aligned pivot pins 1 carries a bar which provides a lug 93 projecting toward the mold part B. The adjacent edge flange 9 of the mold part B carries a roller 95 adapted to ride on the upper surface of the lug 93. In this way the mold part B is brought into proper position in a vertical direction with the mold part A to take care of wear and discrepancies in manufacture in the hinged support for the mold part B. The lug 93, as clearly shown in Fig. 4, has a slight clearance with the adjacent web flange 5 of the mold part B, and this clearance and the sliding contact of the plate 11 of the mold part B with the side bars 31 permit any slight transverse sliding of the mold part B relative to the mold part A necessary to bring the two properly together.

The connections for supplying and discharging the cooling medium are best illustrated by Figs. 1, 2, 9, 10 and 11. As each is like the other, a description of the inlet connection will therefore suffice.

As shown, the edge flange 5 of the mold part A is provided with an opening 97 in communication with the passage afforded by the adjacent hollow rib 27. Detachably secured to the outer side of the edge flange 5 by bolts or screws 98 is a hollow casting 99 having an opening 101 communicating with the opening 97. The inlet connection 29 is connected to a hollow boss 103 forming part of the casting 99. Establishing communication between the interior of the boss 103 and the opening 101 of the casting 99 is a passage 105 so that the cooling medium may flow from the inlet connection 29 through the boss 103 and passage 105 into the passage afforded by the hollow rib 27, it being understood that in the case of the outlet connection the cooling medium flows in the opposite direction from the passage afforded by the

hollow rib 27 to the outlet connection 31 connected to the boss 103.

The casting 99 is further provided with a sleeve portion 107 projecting downwardly from the boss 103, and swiveled interiorly of this sleeve for rotation about an axis in alignment with the axes of the pivot pins 1 is a second sleeve 109. As shown, the sleeve 109 has a portion 111 of reduced cross-section at its inner end to form a shoulder 113 bearing against the bottom of the socket afforded by the sleeve 107. Carried by the outer end face of the sleeve 103 is detachably secured a ring member 115 engaging the outer face of the sleeve 109 for retaining the latter against longitudinal movement relative to the sleeve 107. In the space between the sleeve 107 and the reduced diameter portion 111 of the sleeve 109 is a compressible ring packing member 117 of any suitable construction, this packing being compressed against the wall 119 of the casting 99 when the ring 115 is drawn by the screws 121 against the sleeve 109 to force the latter inwardly against the packing.

Interiorly of the sleeve 109 is shown a metal bellows 123 having a neck portion 125 received in the bore of the reduced diameter portion 111 of the sleeve 109 and welded thereto as at 127. The lower end of the bellows is provided with a similar neck 125, which neck is received in an opening 129 in a second hollow casting 131, this neck of the bellows being welded to the casting as shown at 133.

The casting 131 is detachably secured by bolts or screws 135 to the outer side of the web flange 9 of the mold part B opposite the flange 5 to which the casting 99 is secured, and is provided with an opening 137 in fluid communication with an opening 139 in the flange 9 communicating with the interior of the adjacent hollow rib 27. The casting 131 has a portion, formed with a passage 141, projecting over the lower open end of the sleeve 109, into which passage the lower end of the bellows 123 opens. By so connecting the mold part B with the casting 99 the cooling medium from the inlet connection 29 can flow from the hollow boss 103 through the bellows and into the passage 141 in communication with the cooling medium distributing conduits of the mold part B, and can flow from those conduits in the opposite direction to the outlet connection 31.

The bellows 123 in the above described construction is extensible and contractible longitudinally to permit the mold part B to move vertically relative to the mold part A, and is laterally yieldable to permit the mold part B to be positioned closer to or farther from the mold part A. The construction of the bellows however is such that it resists torsional strains, and causes the sleeve 109 freely to rotate on its bearings when the mold is opened and closed. It will be observed that the sleeves 107 and 109 house the bellows to prevent it from being injured accidentally, and that the casting 131 extends over the opening of this housing further to protect the bellows from injury.

It will be understood that, within the scope of the appended claims, wide deviations may be made from the forms of the invention described without departing from its spirit.

I claim:

1. A mold having, in combination, a pair of mold parts connected for relative swinging and movement transverse to the axis of such swinging, one of which mold parts is provided with a

passage for cooling medium, conduit means for conducting cooling medium supplied to said passage, which conduit means comprises a laterally bendable, torsion resisting, cooling medium conducting sleeve, the axis of which latter is approximately coaxial with the axis of relative swinging of said mold parts, said sleeve at one end thereof being operatively carried by one of said mold parts, and, at its opposite end, being operatively swiveled on the other of said parts for axial rotation relative thereto.

2. A mold having, in combination, a pair of mold parts connected for relative swinging and movement transverse to the axis of such swinging, one of which mold parts is provided with a passage for cooling medium, conduit means for conducting cooling medium supplied to said passage, which conduit means comprises a member operatively swiveled on one of said mold parts for rotation about an axis approximately coaxial with the axes of relative swinging of said parts, and a laterally bendable, torsion resisting, cooling medium conducting sleeve, the axis of which also is approximately coaxial with said axes of swinging for connecting said swiveled member to the other of said parts.

3. A mold according to claim 1 in which the cooling medium conducting sleeve is also longitudinally extensible and contractible.

4. A mold according to claim 2 in which the cooling medium conducting sleeve is also longitudinally extensible and contractible.

5. A mold according to claim 2 in which the swiveled member is a sleeve and the said cooling medium conducting sleeve is positioned within it so as to be housed thereby.

6. A mold according to claim 1 in which the cooling medium conducting sleeve is a longitudinally extensible and contractible bellows.

7. A mold according to claim 2 in which the cooling medium conducting sleeve is a longitudinally extensible and contractible bellows.

8. A mold according to claim 2 in which the swiveled member is an open ended sleeve swiveled within the recesses of a surrounding recessed member carried by one of the mold parts, which sleeve is restrained against substantial axial movement relative to said surrounding member, the cooling medium conducting sleeve being surrounded by the swiveled sleeve and connected at one end thereto, the other mold part carrying a cooling medium conducting member to which the other end of said cooling medium conducting sleeve is connected, the last named member extending over the adjacent open end of said swiveled sleeve.

9. A mold according to claim 2 in which the cooling medium conducting sleeve is a longitudinally extensible and contractible bellows and the swiveled member is an open ended sleeve swiveled within the recesses of a surrounding recessed member carried by one of the mold parts,

which last mentioned sleeve is restrained against substantial axial movement relative to said surrounding member, the cooling medium conducting sleeve being surrounded by the swiveled sleeve and connected at one end thereto, the other mold part carrying a cooling medium conducting member to which the other end of said cooling medium conducting sleeve is connected, the last mentioned member extending over the adjacent open end of said swiveled sleeve.

10. A mold having, in combination, a pair of mold parts connected for relative swinging and movement transverse to the axis of such swinging, one of which mold parts is provided with a passage for cooling medium, conduit means for conducting cooling medium supplied to said passage, which conduit means comprises a fluid conducting section carried by one of said mold parts having an opening facing in one direction of the axis of relative swinging of the mold parts, a fluid conducting section carried by the other of said mold parts having an opening facing in the opposite direction to the opening of the other section in spaced relation therewith, and a flexible conduit placing said openings in fluid communication.

11. A mold according to claim 10 in which one of the fluid conducting sections carried by the mold parts has an open ended sleeve surrounding the flexible conduit, which sleeve extends toward the other fluid conducting section and terminates in proximity thereto.

12. A mold according to claim 10 in which one of the fluid conducting sections carried by the mold parts has an open ended sleeve surrounding the flexible conduit, which sleeve extends toward the other fluid conducting section and terminates in proximity thereto, the flexible conduit being fixed at one end to one of said sections, and, at its opposite end, being swiveled to the other section.

13. A mold according to claim 10 in which the flexible conduit is fixed at one end to one of the fluid conducting sections carried by the mold parts, and, at its opposite end, is swiveled to the other of said sections.

14. A mold according to claim 10 in which one of the fluid conducting sections carried by the mold parts has a sleeve in communication with the opening of said section, which sleeve surrounds said flexible conduit and extends toward the other fluid conducting section and terminates in proximity to the latter, an annular member rotatably carried by said sleeve interiorly thereof, said annular member interiorly thereof being in communication with said opening, the flexible conduit being fixedly connected at one end thereof to said annular member, and, at its opposite end, being fixedly connected to the other of said sections for conducting fluid from one of said sections to the other.

PAUL M. MUELLER.
